CARL RICHARD WALLER, OF TRENTON, NEW JERSEY, ASSIGNOR TO DE LAVAL STEAM TURBINE COMPANY, OF NEW YORK, N. Y., A CORPORATION OF NEW JERSEY.

GOVERNING MECHANISM FOR FLUID-PRESSURE MOTORS.

1,311,931.

Specification of Letters Patent.

Patented Aug. 5, 1919.

Application filed April 6, 1916. Serial No. 89,373.

To all whom it may concern:

Be it known that I, CARL RICHARD WALLER, a citizen of the United States of America, and a resident of Trenton, in the county 5 of Mercer and State of New Jersey, have invented certain new and useful Improvements in Governing Mechanism for Fluid-Pressure Motors, of which the following is a specification.

10 My invention relates to pressure-operated governing means for elastic fluid motors, particularly steam and compressed air turbines, and comprises a pilot-valve-controlled governor valve wherein the motive fluid for 15 operating the pilot-valve-controlled motor of the main governor valve is an elastic fluid, preferably the same elastic fluid which drives the main motor or turbine. Other features of my invention will be pointed out 20 hereafter.

The objects of my invention are to dispense with the usual high pressure oil-supply system commonly provided for operating the governor valves of pilot-valve governing 25 systems; to operate the governor valve by elastic fluid, preferably the elastic fluid which operates the motor; to cause the elastic fluid under pressure which operates the governor valve to also do work in the motor; to avoid 30 condensation in the governor valve mechanism from the fluid so operating the governor valve; and to make the entire mechanism very simple, compact and free from liability to derangement. Other objects of 35 my invention will appear hereafter.

I will now proceed to describe my invention with reference to the accompanying drawing in which a portion of an elastic fluid turbine, a pilot-valve-controlled governor 40 valve therefor, and a centrifugal governor controlling the pilot valve are shown, some of the parts being shown in elevation and others in central vertical section, the drawing being diagrammatic rather than 45 illustrative of actual construction.

At the present time, the practice as to governing a steam turbine of 500 kw. or larger is to use an oil-operated valve gear controlling the governor valve or valves, 50 the pressure against the oil piston of this valve gear being varied as required by means of a pilot valve actuated by a speed governor, usually a centrifugal governor. In the case of valve gear of such type, it is

necessary to furnish means, such for example as a pump, which will maintain the oil used to operate such valve gear under a considerable pressure, usually between 30 and 40 pounds. For lubrication, the turbine is customarily provided with another oil 60 pressure system, maintained at from 3 to 5 pounds pressure. The ordinary method of governing at present in use, therefore, involves two oil pressure systems, with attendant complications. By the invention herein 65 described I dispense with the higher pressure of these oil systems, substituting therefor a much simpler elastic fluid pressure system, the elastic fluid being drawn, preferably, from the supply line by which steam 70 or other working fluid under pressure is supplied to the turbine.

In the drawing, 1 designates the nozzle ring of an elastic fluid turbine, 2 the main high pressure steam chest of that turbine, 75 receiving its steam supply through the main governor valve 4. This valve 4 is of the double balanced puppet type, comprising valve disks 13 mounted on a valve spindle 5, to which spindle is connected a piston 80 6, movable in a cylinder 14. A spring 7 is located in said cylinder 14, above the piston 6, and tends to press that piston and valve disks 13 downward. Steam or other working fluid under pressure is supplied from 85 the inlet side of the valve 4, through a pilot valve 8, to the portion 9 of the cylinder 14 beneath the piston 6. The pilot valve 8 is also of the double balanced puppet type, comprising valve disks 15 mounted upon a 90 spindle 15^a connected by a rocker lever 11 to a speed governor 12, preferably of the centrifugal type.

A conduit 10 leads from the chamber 9 of cylinder 6; and preferably leads from the 95 pipe connection connecting valve 8 with cylinder chamber 9. This conduit 10 is connected to any suitable source of lower pressure, but preferably is connected to an auxiliary steam chest 3 of the turbine, which 100 steam chest 3 is provided with means, such as one or more nozzles 16, whereby the steam so supplied to auxiliary steam chest 3 may do useful work; such nozzle or nozzles 16 being so proportioned that any slight alteration of the position of valve disks 15 will 105 immediately cause change of pressure in steam chest 3, conduit 10 and chamber 9,

which change in pressure will immediately affect the position of piston 6 and valve disks 13.

In order to prevent collection of fluid under pressure behind the piston 6, the portion of cylinder 14 in rear of that piston is connected by a duct 17 to any suitable point of lower pressure; for example a lower stage of the turbine, the exhaust of the turbine, or the atmosphere.

The operation of the governing system is as follows: Before steam is admitted to the valve 4, the valve disks 13 are held closed by spring 7; and the pilot valve disks 15 are held open by the governor 12. When steam is first admitted to valve 4 it will pass immediately through the pilot valve 8 to the chamber 9 of cylinder 14, and there will act upon the piston 6 to raise that piston and with it the valve disks 13 of the main valve 4. When the steam so admitted to cylinder chamber 9 has reached a sufficient pressure to overcome the spring 7, the valve disks 13 will be raised, admitting steam to the main steam chest 2 of the turbine and so starting the turbine, and, consequently, starting the speed governor 12. When the turbine has reached a speed such that the speed governor begins to act upon the pilot valve, it will lower the pilot valve disks 15 more or less, so throttling the steam supply to cylinder 14; and as soon as the steam pressure acting upon the piston 6 decreases materially, valve disks 13 will be closed more or less owing to the action of the spring 7 upon the piston 6, so decreasing the pressure of the steam supply to the main steam chest 2 of the turbine.

It is important that there be a continual bleeding off of steam from the chamber 9 of cylinder 14, both in order to keep the steam in such cylinder 9 hot, so avoiding condensation, and in order that the governing mechanism be not too sensitive. It will be understood readily that if there were no bleeding off of steam from the chamber 9, a very slight opening of the valve disks 13 would keep the piston 6 under full supply pressure, and the action of the governor 12 on pilot valve disks 15 would necessarily be extremely delicate and through a very small range in order that any variation of pressure in cylinder chamber 9 might be ob-

tained. But by bleeding off of steam as by means of pipe 10, a sufficient flow of steam past the valve disks 15 is obtained, so that the action of these valve disks under control of the governor need not be very delicate; while on the other hand the steam thus led off is caused to do useful work, substantially as efficiently as it would do if supplied to the main steam chest of the turbine. It therefore follows that there is no substantial loss in efficiency of the turbine, due to the by-passing of a portion of the steam for the operation of the governor mechanism.

What I claim is:

1. Governing means for elastic fluid motors comprising in combination a main valve casing and a main governing valve therein, a pressure cylinder projecting from and mounted upon said valve casing and pressure-operated means therein for operating said main valve, a pilot valve casing likewise mounted on said main valve casing and projecting therefrom parallel to said pressure cylinder and connected to the main valve casing to receive working fluid therefrom, a pilot valve within such pilot valve casing, a duct connecting such pilot valve casing to said pressure cylinder, and open bleeding off means for said cylinder.

2. Governing means for elastic fluid motors comprising in combination a main valve casing and a main governing valve therein, a pressure cylinder mounted on said main valve casing and pressure-actuated means for operating said governing valve, a pilot valve casing mounted on said main valve casing to receive working fluid therefrom, said pilot valve casing comprising an outer chamber, and an inner chamber ported for a double balanced puppet pilot valve, the axes of movement of said main valve and pilot valve being generally parallel, a duct connecting the inner chamber of said pilot valve casing with said pressure cylinder, and open bleeding off means for said pressure cylinder.

In testimony whereof I have signed this 100 specification in the presence of two subscribing witnesses.
